SILVER CLEANER

Martinus J. Dyrud, Prairie du Chien, Wis.

Application May 27, 1954, Serial No. 30,700

Term of patent 14 years

(Cl. D16—2)

To all whom it may concern:

Be it known that I, Martinus J. Dyrud, a citizen of the United States of America, residing at Prairie du Chien, county of Crawford, and State of Wisconsin, have invented a new, original, and ornamental Design for a Silver Cleaner, of which the following is a specification, reference being had to the accompanying drawing, forming a part thereof, wherein:

Figure 1 is a top plan view of a silver cleaner showing my new design;

Figure 2 is a bottom plan view of the same;

Figure 3 is a sectional view on the line 3—3 of Figure 1;

Figure 4 is a sectional view on the line 4—4 of Figure 1;

Figure 5 is a sectional view on the line 5—5 of Figure 1;

Figure 6 is a sectional view on the line 6—6 of Figure 1, and

Figure 7 is a sectional view on the line 7—7 of Figure 1.

I claim:

The ornamental design for a silver cleaner, as shown.
